UNITED STATES PATENT OFFICE.

SEBASTIAN RITTY, OF DAYTON, OHIO, ASSIGNOR TO A. W. STEVENS & SON,
OF AUBURN, NEW YORK.

SPRING-TOOTH HARROW.

SPECIFICATION forming part of Letters Patent No. 419,971, dated January 21, 1890.

Application filed May 14, 1889. Serial No. 310,784. (No model.)

To all whom it may concern:

Be it known that I, SEBASTIAN RITTY, a citizen of the United States, residing at Dayton, in the county of Montgomery and State 5 of Ohio, have invented certain new and useful Improvements in Spring-Tooth Harrows, of which the following is a specification.

Harrows have heretofore been made with frames composed of metal bars intercepting 10 each other at regular intervals and having curved spring-teeth secured at the points of intersection; and my present invention relates to this class or type of harrows, and more particularly to the manner of securing 15 the frame-bars at the points of intersection and of fastening the teeth at said points, whereby, as will appear from the ensuing description, the removal of the bolts which hold the teeth knocks down the entire harrow, so 20 that the straight frame-bars may be packed or bundled for shipment by themselves and the teeth separately bundled, bringing the whole within small compass.

In the drawings, Figure 1 is a perspective 25 view of a harrow constructed according to my invention, and Fig. 2 is an enlarged detail of the joints between the draft-bars and cross-bars with said bars in position and a pair of the draft-bars united. Fig. 3 is a vertical longitudinal section through one of said joints, and Fig. 4 a vertical transverse section; and Figs. 5 and 6 are respectively enlarged details in top and bottom plan view of the clips at the joint.

35 A represents the draft-bars of a harrow, and B the cross-bars. These are straight bars of iron or steel, preferably rolled with a central longitudinal channel *a* for strengthening—that is to say, the channel is formed by 40 rolling the bar from the plate so as to present a rib on one side and a groove on the other, the rib in the assembled harrow being uppermost in the draft-bars, while in the cross-bars it is undermost, that the flat faces 45 of the bars may be in contact with each other. The forward ends of the draft-bars where they meet are flattened vertically or curved, as at *b*, so as to overlap and be bolted together, although it is evident they may be 50 otherwise secured at this point. To the front

draft-bars are secured the usual draft-clips for the attachment of the drag-bar D, to which the team is hitched.

F is a chair for the reception of the draft-bars of the frame at the points where they 55 intercept the cross-bars. This is in general terms a rectangular plate with the superfluous metal cut away at two points *f*, and having bolt-holes *f'* in each end or wing. A seat F', guarded by snugs *f''*, separated by the 60 width of the draft-bar, runs diagonally across the top of this chair and has two bolt-holes *f'''*, one near the end, but diagonally across from each other, to receive bolts F'', which pass through the draft-bar alternately on 65 each side of its central rib and groove and secure it to the chair. The bolt-holes are 70 advisably countersunk on the upper side of the chair, that the heads of the bolts may lie flush and not interfere with the opposite, and in some respects similar, chairs secured to the cross-bars, as will be presently explained. The under side of this draft-bar chair has also a seat F'', but convex and rounded from the center toward either side 75 of and parallel with the line of draft of the harrow—that is, at such an angle to the length of the chair as to about bisect the angle formed by the union of the draft and cross bars, and this seat constitutes one mem- 80 ber of the tooth-fastening.

G represents chairs converse to those just described, having practically the same outline and cut away for lightness at *g*, with bolt-holes *g'* at each end or wing, and also having 85 a seat G', guarded by snugs *g''*, for the reception of the upper face of the cross-bar. The bolt-holes in the wings are outside of the just-mentioned seat and match the bolt-holes in the wings of the opposing draft-bar chair; 90 but other bolt-holes *g'''* are formed at each end of the seat, but diagonally across from each other, to receive the bolts which unite the chair to the cross-bar. Thus when the draft-bars and cross-bars to which the respective 95 chairs are secured are brought together at the proper angle of intersection, two bolts passing through the holes in the wings will serve to unite said bars and the removal of the bolts will serve to detach them without 100

detaching the chairs from the bars themselves.

The last-mentioned chair—that is, the one secured to the cross-bars—has on its upper face a concave seat G³, matching the convex seat upon the draft-bar chair and at the same angle in the frame, and this second seat constitutes the reverse member of the tooth-fastening.

10 The tooth H is a curved flat spring, such as heretofore used, and without any special novelty in its construction. In securing it to the harrow it is passed into its seat, while the bolts that unite the upper and lower chair-plates together are loosened, and being adjusted to the proper position these bolts are tightened down, when the convex seat on the upper chair will force the shank of the tooth down into the concave seat in the lower chair and clamp it firmly into position, the frame-bars being at the same time and by the same tightening of the bolts firmly secured together at the point where the particular tooth is applied.

15 Should occasion arise for adjusting the tooth or removing and replacing a broken tooth, the nuts on the bolts which unite the chairs together can be loosened, as before, without detaching the chairs themselves from

20 the frame-bars and can be tightened up after the change has been made; but when it is desired to knock down the harrow these bolts will be entirely removed, thus at the same time detaching the teeth and separating the frame-bars, but leaving each of the latter with its respective chair-plates secured in position and ready for reassembling of the harrow at any time. When thus knocked down, the frame-bars can be bundled or bound 25 together separately in small compass and the teeth piled or nested together and also bundled or boxed for shipment.

30 I am aware that metallic chairs have heretofore been used at the intersection of metal frame-bars in various machines—as, for instance, in Letters Patent of the United States No. 17,151, granted April 28, 1857, to M. G. Hubbard, and also that spring-teeth in harrows have been secured above the point 35 of intersection of the frame-bars and above said frame-bars themselves or in seats formed in blocks to receive said frame-bars; but I

am not aware that a harrow has ever been made in which the spring-teeth were secured in seats between said frame-bars at the point 55 where they intersect each other, or in which the removal of the bolts which serve to clamp the teeth in their seats of itself dismantles the harrow by separating the frame-bars.

I claim as my invention—

1. The combination, substantially as hereinbefore set forth, in a harrow, of the metal draft and cross bars, the chairs secured, respectively, to the under faces of the top bars and the upper face of the bottom bars at 65 their points of intersection and having seats for the spring-teeth in their meeting faces, the bolts securing said chairs together independently of the frame-bars, and the spring-tooth clamped between said chairs.

2. The combination, substantially as hereinbefore set forth, of the metal draft and cross bars, the chairs F, secured to one set of said bars and having convex seats, the chairs G, secured to the other set of said bars and having concave seats matching the convex seat on the opposite chair, the bolts passing through wings of said plates outside of the frame-bars to unite them together, and the spring-tooth secured between the convex and 75 concave seats.

3. The combination, substantially as hereinbefore set forth, in a harrow, of the draft-bars longitudinally channeled to form a rib on the upper face, the chairs F, with their 85 diagonal seats secured to said draft-bars by bolts arranged alternately on either side of the longitudinal rib and having concave seats on their under faces, the cross-bars longitudinally channeled to form a rib on 90 their lower faces, the chairs G, having diagonal seats secured to the top of said cross-bars by bolts arranged alternately on either side of said bars and provided on their upper faces with convex seats, the curved spring-tooth, and the bolts passing through the ends or wings of said chairs outside of the draft and cross bars and uniting the whole together.

SEBASTIAN RITTY.
